US00D637916S

(12) **United States Design Patent**
McNabb et al.

(10) **Patent No.:** US D637,916 S
(45) **Date of Patent:** ** May 17, 2011

(54) **BOTTLE**

(75) Inventors: **Richard Paul McNabb**, Milford, CT (US); **Humberto Garcia-Ruiz**, Shelton, CT (US)

(73) Assignee: **The Sun Products Corporation**, Wilton, CT (US)

(**) Term: **14 Years**

(21) Appl. No.: **29/379,519**

(22) Filed: **Nov. 19, 2010**

Related U.S. Application Data

- (60) Division of application No. 29/361,176, filed on May 6, 2010, now Pat. No. Des. 627,655, which is a continuation of application No. 11/260,904, filed on Oct. 28, 2005, now abandoned.
(51) **LOC (9) Cl.** **09-01**
(52) **U.S. Cl.** **D9/543; D9/565; D9/571**

(57) **CLAIM**

The ornamental design for a bottle, as shown and described.

DESCRIPTION

FIG. 1 is a top, rear, and right side perspective view of a bottle showing our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The broken line showing of a bottle closure in the FIG. 1 drawing view and the broken line showing of portions of the bottle in the FIGS. 2-6 drawing views are included for the purpose of showing environmental structure that forms no part of the claimed design.

1 Claim, 6 Drawing Sheets
